No. 805,722.

PATENTED NOV. 28, 1905.

W. S. HAMM & J. A. MOSHER.

LAMP

APPLICATION FILED AUG. 29, 1904.

UNITED STATES PATENT OFFICE.

WILLIAM S. HAMM, OF LAKESIDE, AND JOHN A. MOSHER, OF PARK-RIDGE, ILLINOIS, ASSIGNORS TO THE ADAMS & WESTLAKE COMPANY, A CORPORATION OF ILLINOIS.

LAMP.

No. 805,722.

Specification of Letters Patent.

Patented Nov. 28, 1905.

Application filed August 29, 1904. Serial No. 222,649.

To all whom it may concern:

Be it known that we, WILLIAM S. HAMM, a resident of Lakeside, and JOHN A. MOSHER, a resident of Parkridge, county of Cook, and 5 State of Illinois, citizens of the United States, have invented certain new and useful Improvements in Lamps, of which the following is a specification, and which are illustrated in the accompanying drawings, forming a part 10 thereof.

This invention relates to lamps adapted to be set within the wall of a railway-car and may be designated as a "panel-lamp."

It consists of a suitable frame adapted to be 15 secured to the surface of the wall and incloses an aperture therein, a double back projecting within the wall-aperture and containing an air-chamber, and a front so hinged to the frame that the hinges are not visible, together 20 with means for introducing the illuminant into the chamber of the lamp.

The invention consists, further, in various details of construction, as hereinafter described and as illustrated in the accompanying 25 drawings, in which—

Figure 1 is a central vertical section of the lamp, taken on a plane extending from front to rear. Fig. 2 is a plan section on the line 2 2 of Fig. 1. Fig. 3 is a detail section on 30 the line 3 3 of Fig. 2; and Fig. 4 is a detail front elevation of the lamp, partly in section.

A portion of the inner wall of a railway-car is indicated at 10 10, an aperture being 35 provided therein to receive the back of the lamp. The attaching-frame of the lamp comprises the bottom member 9, the side bars 11, and a cap 12. The side bars 11 are provided with instanding apertured lugs 11^a, as shown in Fig. 4, by means of which the lamp may 40 be secured to the wall of the car by means of screws, and as these lugs are inclosed within the lamp-body the attaching means are not observable. The bottom member is secured to a bracket 13, which is in turn attached to 45 the wall 10 of the car. The side bars 11 are riveted at their lower ends to upstanding lugs formed on the bottom member 9 and at their upper ends to depending lugs from the cap 12, and they are also provided with instanding 50 apertured lugs, through which screws may be passed into the woodwork of the car-wall. The finial 14 is shown as attached to the top of the cap 12.

The back wall of the lamp 15 is preferably

of sheet metal formed to project inwardly 55 through the aperture in the car-wall and having flanges 16 and 17 at its bottom and top, respectively, for engagement between the corresponding members of the lamp-frame and the wall of the car. 60

The front 18 of the lamp bows outwardly, being shown as comprising three flat panels, and fits when closed against the several members of the frame. This front is carried by a pair of link-hinges 19 20, pivoted at their 65 inner ends by means of a pin 21 to hinge-lugs 22 23, projecting inwardly from the side members 11 of the lamp-frame, and at their outer ends to lugs 24 25, projecting inwardly from the lamp-front and at its vertical median line. 70 The pintle 26 securing the lower hinge-link 19 to the lamp-front serves also as a bolt for engaging a suitable socket in the bottom 9 of the lamp to retain the front in its closed position. This pintle is consequently arranged to 75 slide vertically and is spring-depressed, a suitable thumb-piece being shown for raising it sufficiently to disengage it from the socket of the lamp-bottom.

The reflector 27 is preferably of sheet metal 80 and is bowed inwardly, so as to project through the aperture in the wall of the car, but is spaced apart from the back 15, so as to provide an air-chamber 28 coextensive with the back of the lamp. At its upper end the reflector 85 curves forwardly and terminates in the cap 12, which is apertured, as shown at 31, to allow the escape of the vapors of combustion and also provide for circulation through the air-chamber 28. The strong current of vapor 90 from the combustion-chamber induces a flow of air through the chamber 28 and assists in keeping the rear wall of the lamp cool.

The back 15 may have side flanges, as 95 30, which lie between the side members 11 of the lamp-frame and the wall of the car. The side edges of the reflector are preferably continued forwardly beyond the line of the surface of the car-wall and will shade the joint between the side members of the frame and the 100 wall, so that if a close fit is not secured light will not be emitted. The reflector is shown as secured by means of screws 37 passing into the woodwork of the car-wall.

A duct 32 leads from a suitable aperture in 105 the bottom 9 of the lamp to the chamber 28, so as to provide it with a supply of cool air. The bottom 9 is further apertured to supply

air for combustion when gas is used as an illuminant, and these apertures are preferably covered by light-shades 33.

When gas is used as an illuminant, it may 5 be introduced into the body of the lamp by means of a pipe 35, entering through its back, and which is shown in the present instance as provided with an acetylene-gas burner 36.

As thus constructed the lamp may be secured 10 to the wall of a car entirely by means of hidden screws, the bracket 13 having an upstanding wall-plate, which is covered by a foot-piece of the bottom 9, resting upon the sole of the bracket, to which it is secured. The 15 hinges of the lamp-front are entirely inclosed within the body of the lamp, and hence not visible.

The comparatively cool current of pure air issuing from the chamber 28 mixes with the 20 vapors as they issue from the combustion-chamber. It therefore not only immediately dilutes the carbonic-acid gas due to combustion, but also lowers its temperature, so that it will not injure the decorations of the car, 25 thus rendering it feasible to make the front of the lamp approximately flush with the wall. This cooling action makes it possible also to employ decorative effects in connection with the lamp which involve the use of readily-fusible materials, such as lead settings for the 30 glass.

We claim as our invention—

1. As an article of manufacture, a lamp comprising a chambered body portion having 35 a transparent front and opaque back and a laterally-projecting wall-plate intermediate of its front and back, a burner within its body-chamber, and a discharge-flue leading from the combustion-chamber forward of the wall-plate.

2. As an article of manufacture, a chambered lamp-body provided with a laterally-projecting wall-plate and having its back extended back of such plate, and a discharge-flue 45 leading from the combustion-chamber forward of the wall-plate.

3. As an article of manufacture, a chambered lamp-body having a laterally-projecting attaching-plate and bowing backwardly and 50 forwardly from such plate and having a discharge-flue leading from the combustion-chamber forward of the wall-plate.

4. In a lamp, in combination, a back wall, a reflector forward of and spaced apart from

the back wall and terminating at the top within 55 the body of the lamp, and an air-duct leading to the bottom of the chamber inclosed between the back wall and the reflector.

5. In a lamp, in combination, an attaching-frame; a double back extending rearwardly 60 from the frame and comprising a rear wall and a reflector-plate, such members being spaced apart to form an air-flue; and a front attached to the frame and having a bottom apertured to supply air to the flue. 65

6. In a lamp, in combination, an attaching-frame, a back, pivoted links connected to the side of the frame, and a front connected to the ends of the links by means of lugs on its interior. 70

7. In a lamp, in combination, a lamp-body adapted to be secured to a wall and to extend within the same, and having double back walls containing an air-flue such flue opening at its lower end through the bottom of the body and 75 at its upper end within the body.

8. In a lamp, in combination, a lamp-body adapted to be secured to a wall and to extend within the same, and having double back walls and an apertured cap, such walls inclosing an 80 air-flue and the forward wall terminating below the cap whereby an opening for the air-flue is provided within the cap.

9. In a wall-lamp, in combination, an attaching-bracket having an upstanding wall-plate; a lamp-bottom having a depending upturned foot resting on and secured to the bracket; side bars having instanding screw-lugs; a cap secured to the side bars; a bracket projecting rearwardly from the line of the 90 wall-surface; and a front extending forwardly from such line. 85

10. A wall-lamp provided with a body having side flanges for bearing against the surface of the wall intermediate of the front face 95 and back of the body, said flanges being provided with internal attaching-lugs, and a front hinged to the body by internal hinges.

11. In a lamp, in combination, a body, pivoted links connected to the interior of the body 100 adjacent to its side, and a front connected near its vertical median line to the links by lugs on the interior.
